STRIPING DEVICE

Frank P. Ryan, Detroit, Mich., assignor to
 Chrysler Corporation, Detroit, Mich., a corpora-
 tion of Delaware

Application March 14, 1929, Serial No. 346,833

8 Claims. (Cl. 91—62.6)

This invention relates to a striping device and is illustrated as embodied in a device for applying a paint stripe to a surface such as the body of a motor vehicle.

5 An important object of the invention is to provide a device which feeds the fluid to the surface to be striped by gravity and to regulate the flow by means operable by the engagement of the discharge end of the device on the surface to be striped.

10 Another object of the invention is to provide an adjustable guiding means which may be moved toward or away from the discharge end of the fluid distributing mechanism.

15 A further object of the invention is to arrange the fluid distributing mechanism in such a manner that it may be angularly adjusted in relation to its support so that it may be used in making vertical stripes as well as horizontal stripes. The 20 receptacle for supplying the fluid by gravity is angularly movable about its support to insure a gravity feed on the fluid in all positions of the device regardless of the direction of the stripe.

25 Other objects and advantages of the invention, including improvements of the nozzle at the discharge end and adjustable guide, will be more apparent from the following description and claims taken in connection with the accompanying drawing, in which:

30 Fig. 1 is an end elevation of my improved device.

Fig. 2 is a sectional view on line 2—2 of Fig. 1, parts being shown broken away and in elevation.

35 Fig. 3 is a view taken on line 3—3 of Fig. 2 showing a plan view of the mechanism when in operation, parts being broken away and in section.

Fig. 4 is a view corresponding to Fig. 3 showing the device in inoperative position.

40 Fig. 5 is a sectional view taken on line 5—5 of Fig. 2.

Fig. 6 is a sectional view taken on line 6—6 of Fig. 2.

45 Fig. 7 is a view showing a modified form of nozzle to be used in place of the nozzle shown in Fig. 2.

Fig. 8 is a view showing a modified form of a guiding mechanism.

50 Fig. 9 is a fragmentary plan view of a modification of the discharge end of the device.

Fig. 10 is a sectional view on line 10—10 of Fig. 9.

55 Referring to the drawing wherein I have illustrated my improved striping mechanism, the ref-

erence numeral 10 designates a body portion adapted to be rotatably supported at the end of a handle portion 12. One end of the body portion 10 is formed with a frusto-cylindrical flange 14 having a groove 16 in its outer periphery. The flange 14 is received in a cylindrical sleeve 18 on a part 20 to which the support or handle 12 is secured. The inner periphery of the sleeve 18 (see Fig. 1) is provided with pins 22 which are received in the groove 16. Slots 24 in one face of the flange 14 are provided to receive the pins 22 when the device is being assembled. To assemble the body portion 10 in the sleeve 18, the body portion is turned to a position where the slots 24 register with the pins 22. The body portion 15 is then slid forward until the pins 22 are received in the slot 16 and the body portion is then turned so that the grooves 24 are out of alignment with the pins 22.

The body portion 10 is provided with a longitudinal opening 26 to receive a member 28. One end of the member 28 is provided with a sleeve 30 which receives a coil spring 32. A cap 34 is screw threaded onto a boss 36 at one end of the body portion 10. The closed end of the sleeve 25 30 and the closed end of the cap 34 form abutments for the opposite ends of the spring 32. By this arrangement, the spring 32 urges the member 28 outwardly. The upper surface of the body portion 10 is flattened and provided with a cap 38 (see Fig. 3) secured to the housing 10 by screws 39. The cap 38 is provided with a slot 40 which receives an upwardly extending part 42 on the member 28. The end 44 of the slot 40 limits the outward movement of the member 28 by its engagement with the forward face of the part 42. A drilled passage 46 is formed in the member 28 and a drilled passage 48 is formed in the member 42 communicating with the passage 46. The outer end of the part 42 is screw threaded to receive a sleeve 50 having a central opening 52 and a plurality of radial openings 54. One end of a fluid receptacle is received around the sleeve 50 and held for angular movement thereon by a screw 56, closing the outer end of the sleeve 50. An axial opening 58 is provided in the fluid receptacle 60 forming a communication between a chamber 62 and one of the radial openings 54. The axis of the chamber 62 and opening 58 is at an angle of approximately 45 degrees to the axis 50 of the passage 48. A cap 64 is received on the open end of the receptacle 60 and is provided with a plurality of openings 66. Another cap 68 is fitted over the central portion of the cap 64 and is provided with a central opening 70. A 55

50

ball 72 is positioned between the outer face of the cap 64 and the inner face of the cap 68 adapted to close the opening 60 when the device is inverted to prevent the fluid in the container 62 from running out the opening 70. When the device is in the position shown, the ball 72 rests in a groove 74 away from the openings 70 and 66. Such a construction provides a vent for the chamber 60 which permits the fluid in the receptacle 60 to flow by gravity through the opening 58, openings 54, and passages 48 and 46.

A valve in the form of a cylindrical member 76 is received in the discharge end of the member 28 and is provided with a passage 78 adapted to lie in the path of the passage 46 when the valve 76 is in the position as shown on the drawing. When the passage is swung out of the path of the passage 46, by rotating the cylindrical member 76, the fluid is cut off. As a means for rotating the cylindrical member 76, I have provided an arm 80 pivoted at its one end to the member 28 as at 82. The arm 80 is provided with a slot 84 which receives the upwardly extending member 42 and is also provided with a slot 86 which receives a pin 88, in the cap 38 on the body portion 10. The outer end of the arm 80 is provided with a slot 90 engaging a pin 92 in the cylindrical member 76. The slot 86 is formed with a straight portion and a portion disposed at an angle to the straight portion. The annular portion of the slot, co-operating with the pin 88, causes rotation of the cylindrical member 76 when the member 28 is moved axially into the body portion 10. The straight portion of the slot 86 permits further axial movement of the member 28 without further rotating the cylindrical member 76.

At the outer end of the member 28 I have provided a screw threaded boss 94 to receive a nozzle 96 having an opening communicating with the passage 78. The nozzle has been shown detachable so that it may be replaced by another nozzle having a smaller or larger opening, determined by the width of the stripe to be applied. In Fig. 7 I have shown a modified form of nozzle in which a pair of knife edges 98 may be used. A tubular member 100 having one end terminating adjacent the ends of the knife edges 98 is provided in the nozzle 96' to deliver the fluid into a slot 102.

The handle 12, as shown in Fig. 2, comprises a cylindrical member 104 positioned between the part 20 and a lower cap member 106. A pin 108 in the part 20 is received in a slot 110 in the upper face of the cylindrical member 104 to prevent rotation thereof. The lower cap 106 is secured on a hollow externally threaded member 112 and a shouldered screw 114, screw threaded into the part 20, holds the screw 112, cylindrical member 104 and lower cap 106 in position on the part 20. A slot 116 is provided in one side of a cylindrical member 118 and the part 20 to receive a guiding means extending into the cylindrical member 104 and positioned around the screw 112. The guiding means comprises a block 118 having a vertical opening 120 and a radial opening 122. A plunger 124 is received in the opening 122 and a pivoted member 126 is pinned onto one end of the plunger 124. A spring 128 urges the plunger toward the screw threaded member 112. The opposite end 130 of the plunger is provided with screw threads for engagement with the threaded member 112. The member 126 has its inner end in the form of a cam for retracting the plunger away from the screw threaded member 112 when the pivoted member 126 is in a position as shown dotted in Fig. 5. It will be understood

that when the plunger 124 and pivoted member 126 are in a position, as shown in Fig. 2, the screw threaded member 112 may be rotated by turning the lower cap 106, raising or lowering the guiding means. If it is desired to quickly move the guiding means from one position to another, the pivoted member 126 may be turned to a position for retracting the plunger 124 and the guiding member moved upwardly or downwardly without engagement with the screw threaded member. The block 118 is provided with a hollow outwardly extending portion 132, slotted as at 134, which receives a plunger 136, to which is secured a ball end member 138. A spring 140 operating against a plug 141 carried by the block 118 urges the ball member outwardly against the surface of a part to be striped. The ball member 138 is shown attached to the plunger 136 by a screw 142, which may be removed so that the guide or ball end member 138 may be replaced by such a guide member as shown in Fig. 8. In this form of guiding means I have provided a pair of balls 144, both balls being adjustable axially by screws 146 and the one ball being adjustable radially by a screw 148 in a slot 150.

In the operation of the form of my device thus far described, the operator first adjusts the ball guide in proper relation to the nozzle 96 for engagement with a bead close to where the stripe is to be applied, or the ball may be adjusted to engage the bead on which the stripe is to be applied. The device is then pressed toward the work, moving the member 28 in the body portion 10, which movement opens the valve 76 permitting the fluid to flow through the nozzle 96. The stripe is then applied to the part to be striped and when the end of the stripe has been reached, the device is pulled away from the work, the spring 32 urging the member 28 outwardly from the body portion 10, shutting off the flow of fluid. Not only is the liquid fed through the nozzle 96 by gravity, but the fluid is actually pulled through the nozzle by its capillary attraction, particularly in the case of a viscous paint. If it is desired to make a stripe in a vertical direction, the body portion 10 may be turned in the sleeve 18 and the receptacle 60 may be pivoted around the axis of the sleeve 50 to maintain the fluid level in the chamber above the discharge end of the nozzle.

Referring to Figs. 9 and 10, I have shown a modification of the discharge end of the device. This construction is particularly intended to maintain the axis of the nozzle at right angles to the surface upon which the stripe is to be applied. The nozzle 152 is pivoted on a drilled pin 154 and the drilled pin 154 carried by the member 28. A spring 156 is secured on the member 28 and engages one side of the nozzle 152. A guide 158 is carried on the end of the nozzle 152 and is adjustable toward and away from the surface of the work by means of a split collar 160 pinched on the stem of the guide 158 by a screw 162. The outer surface 164 of the guide is adapted to engage the surface of the work and to be in advance of the stripe. Should the operator twist the device or hold the handle in such a position that the axis of the member 28 is not perpendicular to the surface of the work, the nozzle will pivot on the pin 154, always maintaining the axis of the opening through the nozzle perpendicular to the surface of the work. This is caused by a double contact of the tip 96' and outer surface 164 of the guide 158 on the working surface and a slight pressure on the handle toward the work by the operator. The spring 156, exerting a tension 75

on one side of the nozzle 152, will return the nozzle to its normal position with the opening in the nozzle in axial alignment with the opening in the member 28'.

5 It will be understood that various changes, including the size, shape and arrangement of parts, may be made without departing from the spirit of my invention and it is not my intention to limit its scope other than by the terms of the appended 10 claims.

What I claim is:

15 1. A device of the class described comprising, a handle portion, a body portion angularly movable on said handle portion, an axially movable member in said body portion, a fluid container carried by said member, a nozzle at the end of said axially movable member, said member being provided with a passage connecting the fluid container and the nozzle, and an angularly movable valve in said member to control the flow of 20 fluid through said nozzle.

25 2. A device of the class described comprising, a handle portion, a body portion angularly movable on said handle portion, an axially movable member in said body portion, a fluid container carried by said member, a nozzle at the end of said axially movable member, said member being provided with a passage connecting the fluid container and the nozzle, and an angularly movable valve in said member to control the flow of 30 fluid through said nozzle, a control for said valve, and means for operating said control by the axial movement of said member.

35 3. A device of the class described comprising, a handle portion, adjustable guiding means carried by said handle, a body portion angularly movable on said handle portion, an axially movable member in said body portion, a fluid container carried by said member, a nozzle at the 40 end of said axially movable member, said member being provided with a passage connecting the fluid container and the nozzle, and an angularly movable valve in said member to control the flow of fluid through said nozzle.

45 4. A device of the class described comprising, a body portion having a longitudinal opening therein, a member axially movable in said opening, a nozzle on said member, a fluid container,

said member having a passage forming a communication between said nozzle and said fluid container, a rotary valve in the passage of said member and a connection between said valve and said body portion for controlling said valve by 5 the axial movement of said member.

5. A striping device comprising a support, a reciprocating member in said support, a discharge nozzle on said member, a fluid receptacle on said member, said member having a passage 10 forming a communication between said receptacle and said nozzle, a rotary valve in said member to control the fluid flow through the passage, an arm having a slot therein pivoted at one end on said member, a pin on said support extending 15 into the slot, and a connection between the valve and the opposite end of said arm.

6. A striping device comprising a support, a reciprocating member in said support, a discharge nozzle on said member, a fluid receptacle 20 on said reciprocating member, said member having a passage forming a communication between said receptacle and said nozzle, and resilient means between said reciprocating member and said support for urging said reciprocating member 25 outwardly.

7. A striping device comprising a support, a reciprocating member in said support, a discharge nozzle pivotally supported at the end of said reciprocating member, a fluid receptacle on 30 said reciprocating member, said member having a passage forming a communication between said receptacle and said nozzle, a valve in the member to control the flow of fluid through said passage, and means operated by the reciprocation of said 35 member for opening and closing said valve.

8. A device of the class described comprising, a handle portion, a member rotatably movable about its own axis at the end of said handle portion, a nozzle at the end of said rotatable member and a rotatable fluid receptacle on said rotatable member extending axially at an angle of approximately forty-five degrees to the axis of said member, said member having a passage forming 40 a communication between said nozzle and said 45 receptacle.

FRANK P. RYAN.
